1

The invention relates to improvements, modifications and additions to the devices and circuits described in my copending application, Serial Number 735,953, filed March 20, 1947.

In this copending application were described electron discharge devices in which the electronic flux assembled in an electron beam was deflected in order to strike at different points of a collecting structure, with suitable focussing at each point of impact.

These arrangements in particular employed structures for the concentration of the electronic flux, consisting of two parallel plates in the form of the arcs of coaxial cylinders between which the said electron flux was transmitted, and the deviation of the electronic beam was ensured in certain embodiments by the variation of the potential of one of these plates, preferably the plate with the greatest radius.

It is one of the objects of the present addition to provide improved devices employing such a structure of concentrating and deviating electrodes.

The copending application mentioned above also described the means for controlling the deflection of the electronic beam of such tubes, particularly by means of electrical current impulse transformer, into deflection control potentials.

It is another object of the invention to provide improved control circuits for certain structures described in said patent application and for the structures described in the present invention.

The invention will be explained in detail in the following description given in relation to the attached drawings in which:

Fig. 1 represents an electron discharge structure similar to that shown in Fig. 3 of the above mentioned copending application.

Fig. 2 represents a circuit incorporating characteristics of the present invention, to control the operation of the device of Fig. 1;

Fig. 3 represents a modification in accordance with certain characteristics of the present invention, of the structure in Fig. 1, or more generally, of any one of the electron discharge device structures provided in the copending application.

Figs. 4 and 5 show curves employed in the explanation in relation to this modification of structure; and,

Fig. 6 represents another example of a circuit more particularly arranged to be used to control the operation of an electron discharge device structure incorporating characteristics of the present invention.

2

Referring first of all to Fig. 1, the embodiment of an electron discharge device shown comprises a cathode 1, of which one surface only is active on account of the presence of the electrode 2 which is maintained in the vicinity of the potential of the cathode 1, or at the same potential. This electrode consists of a cylinder of the same axis as a longitudinal axis of the cathode having an elongated opening in front of the surface of the cathode, of which the emission is to be utilised. Concentric with this electrode is another cylindrical electrode 3, having an opening aligned with the opening of the electrode 2, and brought to a suitable potential in order to accelerate the electrons emitted. Two concentric cylindrical plates 4 and 5 are arranged so that the electronic flux from the cathode 1 passes between them the axis of the structure generating the electronic flux being midway between the two plates 4 and 5. These plates are extended on a length of arc of about 127° in order to obtain the desired effect of concentration of the electronic flux coming from the structure generating and accelerating electrons on one of the collecting electrodes 6a, 6b, 6c. The plate 4 is kept at a positive potential with respect to the cathode, and the plate 5 at a negative potential or slightly positive potential with respect to the cathode, which ensures an effective concentration of the electronic beam on the plate 6.

In this structure, as described in more detail in the above named application, in order to vary the position of the beam from one collecting electrode to another, it is possible to vary the potential of the electrode 5 by applying to this electrode a potential derived from the control potential or the electric control impulses. The circuits which will be described in the following will employ this electrode 5 as variable electrode, although an additional electrode may be provided for this purpose. Nevertheless the structural modification of the device itself forming a part of the present invention, is only of particular interest for the devices in which the electrode 5 is employed as radial deflection electrode of the electronic beam. Moreover, although this modification of structure is described in the present specification in relation to the structure of Fig. 1, it is clear that it is not limited thereto but may obviously be applied to all the structures described in my copending application and comprising the use of the electrode 5 or of the special corresponding electrode as radial deflection electrode.

55 A method of operation of an electron discharge

device with radial deflection such as that shown in Fig. 1, will first of all be described with reference to Fig. 2 which represents a circuit for control by electrical impulses of a device of this kind in accordance with certain characteristics of the invention. The control system of this kind, by electrical impulses transformed into electrical potentials determined on a deflecting electrode may be employed in telegraph or telephone systems, remote control or indicating systems, etc., the number of collector elements 6 of the structure being adapted to be modified as desired and provided in order to fulfill the particular requirements of the system in which the device is employed.

An impulse dial 1, the details of which are not shown and which may consist of any suitable impulse transmitting dial, for example a dial with normally open impulse contacts, is connected by the line 8 to an impulse repeating relay 9 by a series circuit comprising the battery 13 connected to earth, one winding of the relay 9, one wire of the line 8, the impulse transmitting contacts of the dial 1 (not shown), the other wire of the line 8, the other winding of the relay 9, and earth.

The relay 9 is provided with a set of contacts comprising an armature 10 associated with a back contact 11 and a front contact 12. When no impulse is sent from the impulse dial 1, the armature 10 is on the contact 11 and the condenser 15 is charged through the resistance 14 by the battery 13. When an impulse is transmitted the relay 9 is energised, its armature comes into engagement with the contact 12, and the condenser 15 is connected through the resistance 14 and the contact 12 in parallel with the high capacity condenser 16 to the plate of the gas discharge device 17, which for example, may consist of a gas triode of the well-known type, of which the grid is polarised by a battery 18, and to the deflecting electrode 5 to which it applies a potential which causes the displacement of the electronic beam of the device for radial deflection from the position it occupies in an adjacent position, for example causes the displacement of the beam from the electrode 6a to the electrode 6b.

In the embodiments shown the electrode 2 of the electron discharge device is shown grounded together with the cathode, while the accelerating electrode 3 is connected to the low potential BT and the collecting electrodes to the high potential HT through the measuring apparatus Ia, Ib, Ic, source HT being also connected to the electrode 4 of the device.

Assuming that the normal position of the electronic beam of the discharge device is on the electrode 6a when a first impulse is sent from the dial, the circuit of the relay 9 is closed by the contacts of the dial (not shown) and the relay operates, attracting its armature to the work contact 12. The condenser which had been charged by the battery 13 by means of the contact 11, and which moreover has been chosen of such value in relation to the resistance 14, that it has been charged in a practically instantaneous manner by the battery 13 is now connected to the electrode 5 of the electron discharge device and to the condenser 16 and the gas discharge device 17 in parallel. It consequently applies a fixed potential to the electrode 5, which ensures a deviation of the electronic beam of the electronic discharge device from the collecting electrode 6a to the collecting electrode 6b. It will remain there on account of the charge of the condenser 16 under the action of the condenser 15 once the

condenser 15 has returned to position of charging by the battery at the time of the retraction of the armature 10 on the contact 11 on account of the de-energisation of the relay 9 by opening of the circuit of this relay on the contacts (not shown) of the dial. The condenser 16, under the effect of the charge of the condenser 15, takes a charge which is not sufficient to affect the ionisation of the gas discharge device 17 as a result of suitable adjustment of the grid bias applied to the grid of the latter by the battery 18.

Upon occurrence of the second impulse sent by the operation of the dial 1, the same operation will take place and the beam will be directed, 15 under the action of the potential applied to the electrode 5, so as to fall on the collecting electrode 6c, since this potential will result from the two successive charges brought by the condenser 15 to the condenser 16, which cannot again be discharged through the device 17 in parallel.

Upon the third impulse sent by the dial 1, the relay 9 will operate, but then the contribution of the charge of the condenser 15 on the condenser 16 will give the latter such a difference of potential on the terminals that it will overcome the polarisation potential of the discharge device 17 and will effect the ionisation of the latter. The condenser 16 will be discharged through the device 17, and consequently no potential will any longer be applied to the electrodes 5 and the beam will return to normal position on the collecting electrode 6a.

In one embodiment the gas discharge device 17 consisted of a mercury, argon, neon, or other gas-vapor relay, of which the battery potential 18 was adjusted so that the relay became conductive when the potential applied to the condenser 16 exceeded 90 volts, in order to discharge the condenser 16. The plate 5 was at a zero potential in order that the beam might fall on the collecting electrode 6a, at a positive potential of 50 volts in order that the beam might fall on the collecting electrode 6b, and of plus 80 volts in order that the beam might fall on the collecting electrode 6c.

Applicant has however found that during the operation described, and which may be generalised for all the structures of the application referred to above, the current on the electrode 5 was not zero and the result was that the condenser 16 did not strictly retain its charge, but was charged or discharged according to the direction of the current on the plate 5. The current in this circuit consisted in the first place of primary electrons coming from the electronic flux of the cathode 1 of the valve, and in the second place of secondary electrons coming from the plate 5, collected by the plate 4, which is at a higher positive potential.

Consequently, the invention also supplies means and structures of electron discharge devices in order to eliminate these parasitic currents in the plate 5 and consequently to increase the stability and good operation of these devices.

Generally speaking, the modification of the structures with radial deflection provided in the present invention, consists in the realization of structures in which the radial deflection electrode is removed from the position which it occupied in the structures of the above named application, by such a displacement, and brought to such a constantly negative or zero potential with respect to the cathode that all variations of potential on this electrode are in the inverse sense of the potential variation produced thereon

in previous control systems of radial deflection tubes.

It is, in effect, known that in a co-cylindrical structure the distribution of potential may be expressed by:

$$E_r = E_1 + (E_1 - E_2) \frac{\log \frac{r}{R_1}}{\log \frac{R_2}{R_1}}$$

in which relation E_r represents the potential along a cylinder of any radius r comprised between the two extreme radii R_1 and R_2 of the structure, E_1 representing the potential of the electrode of radius R_1 . These notations will be more clearly understood with reference to Fig. 3, which shows such a co-cylindrical structure as that used in a device of the present invention in order to concentrate and deflect the electronic beam.

The variation ΔE_r of the potential at one point of radius r in terms of the variation of potential ΔE_2 along the cylinder of radius R_2 may be expressed as follows:

$$\Delta E_r = \frac{\log \frac{r}{R_1}}{\log \frac{R_2}{R_1}} \Delta E_2$$

It will be seen that ΔE_r is a linear function of ΔE_2 if the dimensions of the structure are maintained constant.

In Fig. 4 the ratio of the variations of potential

$$\frac{\Delta E_r}{\Delta E_2}$$

in ordinates is represented in terms of the ratio R_2/R_1 in abscissae, for different values of the ratio r/R_1 . It will be seen from these curves that it is possible to give the plate 5 a greater radius in the electrode structure 4-5 and a slight change of potential of the plate 5 only is sufficient to obtain the same deflection of the beam. For example, referring to Fig. 4, the variation ΔE_r is 75% of ΔE_2 when R_1 is equal to 7.5; r to 19.5; and R_2 to 27.

In Fig. 5, the values of R_2 in mm. are plotted in ordinates in terms of the values of R_1 in mm. for two different values of the ratio with a difference of radii $r-R_1$ constant. It will be seen that for each ratio there is an optimum value of R_1 which gives a minimum value for R_2 . Such curves might be traced for any desired value of the ratio. The existence of a minimum value of R_2 is important in order to obtain tubes of small dimensions.

Consequently, in order to avoid the drawback mentioned above, of the passage of current in the plate electrode 5, this electrode is taken of a greater radius than the normal radius for which the generator structure of the beam had its axis A coinciding with the axis of the cylindrical structure of the plate electrode, but it will be then brought to a potential defined by the above curves in order to create in its original position a potential surface of the same value as in the case in which it was provided at this position, the axis A remaining in its original position.

In its new position the electrode 5 is always at a zero or negative value with respect to the potential of the cathode, and consequently can never receive current from the cathode while ensuring a correct concentration of the electronic beam on the collecting electrodes 6a, 6b, 6c. The result is that the condenser 16 will not be charged or discharged by an interference cur-

rent in the electrode 5, but will remain at a constant charge value, and that the deflection of the beam will not vary in time once determined by the impulses coming from the transmitting dial 7.

- It should be understood that this modification of structure is not limited to the tube structure of Fig. 1, but can, on the contrary, be employed with advantage in all electron discharge devices considered in the copending application, and, generally speaking, in all electron discharge devices employing a pair of parallel electrodes for the concentration of the electronic beam in which the potential of one electrode is modified in order to ensure stable deflection of the beam.

Fig. 6 shows an example of a control circuit of a modified discharge device in accordance with characteristics of the invention, this circuit being able to be employed, preferably instead of the circuit of Fig. 2, for the control of these tubes.

This circuit is relatively similar to that of Fig. 2, but now it is the positive terminal of the condenser 16 which is earthed and the negative terminal on the new electrode 5' of the electron discharge device, in which the original position of the electrode 5 has been indicated in broken lines. The dimensions and the potentials applied to the electrodes 4 and 6 of the electron discharge device are chosen so that the potential along the surface indicated by broken lines is approximately positive by 80 volts with respect to the cathode 1 when the potential on the terminals of the condenser 16 is zero. This value, moreover, may be different from 80 positive volts, according to the case, and should simply correspond to the value for which the electronic beam is attracted to the collecting electrode 6c when the circuit is at normal. The operation of the circuit will then be similar to that of Fig. 2, with the exception that after the first impulse the electrode 5' will be negative with respect to the cathode, consequently the potential along the surface indicated in broken lines will be less positive with respect to the cathode and the beam will be brought on to the electrode 6b. In the same way, the second impulse will bring the beam on to the electrode 6a, and the third, discharging the condenser 16, through the gas discharge tube 17, will cause the electronic beam to return to the electrode 6c.

This method of control of the device with radial deflection may also be employed for any device with radial deflection and not merely for that device shown diagrammatically in Fig. 6.

Other modifications and adaptations may be employed without departing from the scope of the invention.

I claim:

1. A system for electronic switching, comprising electron beam switching means including a pair of deflecting electrodes and a plurality of target anodes disposed therebetween, one of said electrodes normally being kept at a fixed potential and the other electrode being at a distance from said one electrode such that its potential with respect thereto is of a value as to at least inhibit current flow therein due to attraction of any of the electron emission of said switching means and due to secondary electrons attracted from said other electrode to said one electrode, and means for supplying voltage impulses to said other electrode including means for additively storing said voltage impulses, whereby the potential of said other electrode is successively varied

to effect a deflection of the electron toward target electrodes substantially adjacent to said other electrode.

2. A system according to claim 1, wherein said voltage impulse supplying means further includes a main and an auxiliary potential storage device having each a positive and a negative terminal, said negative terminals being connected to said other electrode, and relay means for discharging said main storage device upon attainment thereon of a given potential.

3. In an electronic switching system, in combination, an electron-emitting cathode, focusing means for the electrons emitted by said cathode, said focusing means including a first and a second deflecting electrode between them defining a path for said electrons, a plurality of target electrodes positioned in said path, output means connected to certain of said electrodes, circuit means for maintaining said target electrodes and said first deflecting electrode at a positive potential relative to said cathode, and input means adapted to apply a plurality of different deflecting potentials to said second deflecting electrode, the most positive of said deflecting potentials being not more positive than the potential of said cathode.

4. The combination according to claim 3 wherein said deflecting electrodes are a pair of coaxial cylinder segments, said cathode being located closer to said first than to said second deflecting electrode.

5. The combination according to claim 4 wherein the radius of said first deflecting electrode is less than the radius of said second deflecting electrode.

6. In an electronic switching system, in combination, an electron-emitting cathode, focusing

means for the electrons emitted by said cathode, said focusing means including a pair of deflecting electrodes in the form of coaxial cylinder segments, said segments between them defining a path for said electrons, a plurality of target electrodes positioned in said path, output means connected to said target electrodes, circuit means for maintaining said target electrodes and the inner one of said deflecting electrodes at a positive potential relative to said cathode, and input means adapted to apply a plurality of different deflecting potentials to the outer one of said deflecting electrodes, said input means including a gas discharge tube having a variable-voltage electrode connected to said outer deflecting electrode, the potential on said variable-voltage electrode being arranged to vary between an ionization potential and an extinction potential the more positive of which is not more positive than the potential of said cathode.

7. The combination according to claim 6 wherein said gas discharge tube has a cathode representing said variable-voltage electrode.

TREVOR H. CLARK.
